UNITED STATES PATENT OFFICE.

GEORGE H. ROBERTS, OF THOMAS, OKLAHOMA.

WHIFFLETREE-HOOK.

1,037,322.

Specification of Letters Patent.

Patented Sept. 3, 1912.

Application filed April 17, 1912. Serial No. 691,353.

To all whom it may concern:

Be it known that I, GEORGE H. ROBERTS, a citizen of the United States, residing at Thomas, in the county of Custer and State of Oklahoma, have invented certain new and useful Improvements in Whiffletree-Hooks, of which the following is a specification, reference being had to the accompanying drawings.

10 This invention relates to new and useful improvements in whiffletree hooks, the object of the invention being to provide a hook of this character which is adapted to securely hold the trace upon the end of the 15 swingletree and prevent the trace from becoming accidentally unhooked from the end of the swingletree.

Another object of the invention is to provide a device of this character which will 20 possess advantages in points of efficiency and durability, is inexpensive of manufacture and at the same time is simple in construction and operation.

With the above and other objects in view 25 the invention consists in the novel features of construction and the combination and arrangement of parts hereinafter more fully described, pointed out in the claims and shown in the accompanying drawings in 30 which,

Figure 1 is an elevation of one end of a swingletree showing my improved hook applied thereto. Fig. 2 is a sectional view on the line 2—2 of Fig. 1. Fig. 3 is a detailed perspective view of the retaining member.

Referring more particularly to the drawings, 1 indicates a metallic ferrule adapted to be applied to the end of the whiffletree 2. 40 Centrally arranged in the closed end of the ferrule is the screw 3 adapted to be screwed into the end of the whiffletree to hold the ferrule securely in place, the outer end of the screw being formed smooth and extends 45 out beyond the end of the ferrule and over which the end of the trace 4 is adapted to be hooked.

Formed on the ferrule and arranged at 50 diametrically opposite points are the outwardly extending lugs 5 and 6. Pivotal secured to the lug 5 by means of the rivet 7 is the angular bar 8 having the opening

9 formed therein, which, when the bar is swung to a closed position is adapted to receive the outer end of the screw 3. Secured 55 to the free end of the bar 8 by means of the rivet 10 is the spring plate 11, said plate being provided adjacent its free end with the spaced ribs 12 which are adapted to engage upon each side of the lug 6 to hold the bar 60 8 securely upon the outer end of the screw 3 and prevent the trace 4 from becoming accidentally unhooked from the end of the swingletree.

In the operation of the device, the trace 65 4 is first hooked over the outer end of the screw 3 and the bar 8 is swung across the end of the swingletree, the outer end of the screw engaging the opening 9, and the ribs 12 engaging with the lug 6 to hold the bar 70 securely in place. It will be seen that the free end of the plate 11 is curved slightly as shown at 13 so that the same can be easily grasped to release the ribs 12 from the lug 6 when the trace is to be unhooked 75 from the swingletree.

While I have shown and described the preferred form of my invention it will be obvious that various changes in the details of construction and in the proportions may 80 be resorted to for successfully carrying my invention into practice without sacrificing any of the novel features or departing from the scope thereof.

What I claim is:—

1. In a device of the character described, 85 the combination with a swingletree, of a ferrule rigidly secured to the end thereof, lugs formed on the ferrule at diametrically opposite points, an angular bar pivotally secured to one of said lugs and having one of its ends disposed across the end of the swingletree, a spring plate rigidly secured to the free end of said bar, spaced ribs formed on the outer end of the plate and adapted to 90 engage with one of said lugs to hold the bar in an operative position, and means projecting from the end of the swingletree to retain the trace in position between said bar and the swingletree.

2. In a device of the character described, 95 the combination with a swingletree, of a ferrule, a screw centrally arranged therein, having its threaded end screwed into the end

of the swingletree and the other end extending beyond the closed end of the ferrule, lugs formed on the ferrule at diametrically opposite points, an angular bar pivotally secured to one of said lugs, said bar having an opening formed therein to receive the outer end of the screw and means carried by the free end of the said bar and adapted

to engage the other lug to hold the bar in an operative position.

10

In testimony whereof I hereunto affix my signature in the presence of two witnesses.

GEORGE H. ROBERTS.
